LOCK FOR LUGGAGE CASE

James M. Powell, Anaheim, Robert S. Inlow, Pasadena,
Tim M. Uyeda and Robert K. Fujioka, Los Angeles,
Calif., assignors to Shwayder Bros., Inc., Denver, Colo.,
a corporation of Colorado

Application September 23, 1957, Serial No. 47,829

Term of patent 14 years

(Cl. D87—2)

FIG. 1.

FIG. 2.

FIG. 3.

FIG. 4.

Fig. 1 is a front perspective view of a luggage case provided with a lock embodying our new design;

Fig. 2 is a top plan view of the lock constituting our new design;

Fig. 3 is a fragmentary side elevation of the luggage case of Fig. 1; and

Fig. 4 is a fragmentary end elevation of the upper portion of the luggage case.

The dotted line showing of the luggage case is for purposes of illustration only.

We claim:

The ornamental design for a luggage case, as shown and described:
